INVENTOR

FIG. 1.

Vernon G. Converse.

UNITED STATES PATENT OFFICE.

VERNON G. CONVERSE, OF PITTSBURG, PENNSYLVANIA.

DESIGN FOR A TRANSFORMER-CASE.

SPECIFICATION forming part of Design No. 32,258, dated February 20, 1900.

Application filed September 1, 1899. Serial No. 729,257. Term of patent 7 years.

To all whom it may concern:

Be it known that I, VERNON G. CONVERSE, a citizen of the United States of America, and resident of Pittsburg, Allegheny county, Pennsylvania, have invented a certain new and original Design for Transformer-Cases, of which the following is a specification, reference being had to the accompanying drawings, forming part of this specification.

My invention relates to transformer-cases; and it consists in an article having the unitary design consisting of a cylindrical body provided with ornamental flutings or corrugations, a base on which said body rests, a top ring having a vertical flange extending up from the same within the outer periphery of the ring, and a cover on said flange.

In the accompanying drawings, forming part of this specification, Figure 1 is a perspective view of a transformer-case embodying my design, and Fig. 2 is a cross-section.

2 is the cylindrical body, provided with the ornamental flutings or corrugations 3.

4 is the base, 6 the top ring, and 7 the vertical flange extending therefrom. 25

8 is the cover on the flange.

9 are bushings extending from the cover 8.

10 is a ring upon the cover, and 11 a lid on the cover.

12 are eyebolts projecting up from the top 30 ring 6 alongside the flange 7.

I claim—

The design for a transformer-case as herein shown and described.

Signed by me at Pittsburg, Pennsylvania, 35 this 30th day of August, 1899.

VERNON G. CONVERSE.
